UNITED STATES PATENT OFFICE.

GIUSEPPE GUARNIERI, OF NEW YORK, N. Y., ASSIGNOR OF ONE-SIXTH TO ANTONIO RAGAZZO.

AUTOMATIC RAILROAD GATE.

Application filed April 5, 1928. Serial No. 267,494.

This invention relates generally to rail-ways and has more particular reference to a novel automatic mechanical railroad gate.

The invention has for an object the pro-
5 vision of a device of the class mentioned
which is of simple durable construction, de-
pendable and efficient in action, and which
can be manufactured and sold at a reason-
able cost.

10 In the following description and in the
accompanying drawings, the device is shown
applied to four railway tracks, but it should
be clear that this showing is not intended as
a limitation. A gate element is applied to
15 opposite sides of the tracks at a crossing.
Each gate element consists of a central tower
provided with a pair of pivoted and oppo-
sitely directed arms.

These arms have swingable stop signs at-
20 tached and in their lowered positions signify
that cross traffic should halt. Provision is
made for vehicles caught between the gate
elements in closed positions for safe pas-
sage.

25 In the open position of the gate elements
are arms are latched in vertical position.
Along the tracks a considerable distance
from the gate elements, trip devices are ar-
ranged and connected by cables with the
30 latching means just mentioned for releasing
the arms, when acted upon by an approach-
ing train. When released the arms are ar-
ranged to assume horizontal positions.

Other trip devices are arranged a con-
35 siderable distance from the gate elements
and connected by cables with the arms for
raising the arms, when acted upon by a
leaving train. Thus the gates are operated
40 automatically by mechanical means, which
insures a great degree of reliance.

For further comprehension of the inven-
tion, and of the objects and advantages
thereof, reference will be had to the follow-
45 ing description and accompanying draw-
ings; and to the appended claims in which
the various novel features of the invention
are more particularly set forth.

In the accompanying drawings, forming
a material part of this disclosure:

50 Fig. 1 is a fragmentary perspective view
of rail tracks and the gate device.

Fig. 2 is a fragmentary longitudinal ver-
tical sectional view of one of the gate ele-
ments.

55 Fig. 3 is a plan view of the rail tracks

and the gate and a schematic showing the
trip devices connected with the gate.

Fig. 4 is a fragmentary horizontal sec-
tional view, taken on the line 4—4 of Fig. 2.

Fig. 5 is an enlarged detail view of a por-
tion of Fig. 3, one trip casing being shown
in horizontal section.

Fig. 6 is an enlarged detail view of an-
other portion of Fig. 3, one trip casing be-
ing shown in horizontal section.

Fig. 7 is a longitudinal vertical sectional
view of the trip device shown in Fig. 5.

Fig. 8 is a longitudinal vertical sectional
view of the trip device shown in Fig. 6.

The reference numeral 10 indicates gen-
erally tracks for trains running in one di-
rection, and 11 represents tracks for trains
running in the opposite direction. In the
center of a road transversely crossing the
70 tracks and on opposite sides of the tracks,
vertical towers 12 are positioned along the
edges of the road and on opposite sides of
the towers 12, vertical posts 13 are located.

The towers 12 have side lugs 14 to which
80 arms 15 are pivotally connected. These arms
are arranged on opposite sides of the tow-
ers and the free ends thereof normally rest
upon the posts 13 for assuming their hori-
zontal position.

Tubular members 16 are pivotally con-
85 nected to the towers 12, and rods 17 slidably
mounted therein are normally urged out-
wards by expansion springs 18. The outer
ends of the rods have elongated slots 19 in
which pins 20 engage, these pins being ar-
90 ranged on the arms 15.

The towers 12 are of hollow construction
and a pair of latch arms 20 are pivotally
supported within each of the towers, inter-
mediate of their ends, the free catch ends 95
thereof projecting thru openings in the side
of the towers. Bars 21 as clearly seen in
Fig. 1 are secured to the arms 15 and ar-
ranged to engage the catch ends of latch
100 arms 20 for supporting the arms 15 in verti-
cal positions.

Springs 22 normally urge the latch arms
20 into operative positions. The inner ends
of the latch arms 20 are connected to links
23 connected with cables 24 guided over pul-
leys 25 and then joining cables 26 leading
105 to trip devices 27 hereinafter more fully de-
scribed.

From certain of the arms 15, upturned end
portions 28 project from opposite sides into 110

the towers thru slots in the sides of the towers. In the horizontal position of the arms 15, the end portions 28 support platforms 29 provided with vertical rods 30 supporting 5 stop signs 31 arranged to be visible in that position thru openings in the towers. In the vertical position of the arms 15, the end portions 28 support the platforms 29 in lowered position so that the stop signs 31 10 are not visible.

The end portions 28 are connected with cables 32 guided over the pulleys 25 and then joining cables 33 leading to trip devices 34 hereinafter more fully described.

15 Referring to the gate element on the near side of the tracks, reference being had to Fig. 1, the left hand arm 15 thereof has a flexible member 35 attached thereto and guided over a pulley 36 on the top of the 20 tower 12. The right hand arm 15 of the gate element on the far side of the tracks, has a flexible member 37 attached thereto and guided over a pulley 38 on the top of the tower 12.

25 Stop signs 39 are swingably mounted on the lower ends of the arms 15. A vehicle of ordinary height caught between the gate elements when the arms 15 are lowered may continue to travel and pass beneath the arms 30 15, the stop signs 39 being swung away by the vehicle during its passing. If the vehicle is too high to permit passage beneath the arms 15, the free ends of the flexible members 35, 37 may be pulled by a party 35 for sign to the vehicle to temporarily raise the arms 15 and permit passage. Quite obvious the escape of a vehicle caught between the gate elements depends upon sufficient time 40 with respect to an approaching train.

45 Each of the trip devices 27 consists of a casing 40 formed with a slot 41 thru which a trip 42 projects from within the casing. This trip is pivotally connected to a block 44 slidably mounted on rods 43 supported in the casing. The trip is held in vertical 50 position by a wheel 45 arranged to engage in a cavity 46 for lowering the trip 42. Cable 26 is attached to the block 44.

55 Each of the trip devices 34 consists of a casing 50 formed with a slot 51 thru which a trip 52 projects from within the casing. This trip is pivotally connected to a block 54 slidably mounted on rods 53 supported in the casing. The trip is held in vertical position by a wheel 55 arranged to engage in a cavity 56 for lowering the trip 42. Cable 33 is attached to the block 54.

60 The operation of the device may be traced by first assuming the arms in a vertical position and thus held by the catches 20. A train approaching the crossing moves a trip 42 located at a suitable distance from the crossing, forward until wheel 45 drops into the cavity 46 and immediately thereafter 65 the trip 42 is moved back into its original

position by a pull on the cables 24 and 26 instigated by a spring 22. The train moving of trip 42 is communicated by cable 26 to the cables 24 and catches 20 for releasing the arms 15 from latched vertical position. 70 Springs 18 and gravity act to lower the arms which are counterbalanced by the cables 32 and 33 and the blocks 54, and the arms assume lowered positions very slowly.

A train leaving the crossing moves a trip 75 52 which is preferably located at a greater distance away from the crossing than trip 42, forward until wheel 55 drops into the cavity 56. This forward motion is communicated by cables 33 and 32 to the extensions 28 for raising the arms back to vertical position. Springs 22 act to urge the catches 20 into latching position so as to be in operative position for the next train.

80 It is pointed out that when an approaching train moves the trip 42 forwards the cable 26 will be drawn, which motion is transmitted to cable 24

85 transmitted to cable 24 which then moves downwards and causes the latch members 20 to release the gate arms. Immediately 90 after the train trip passes over the trip 42 the springs 22 will act to draw the cable 24 upwards which motion is transmitted to cable 26 and the trip 42 is drawn rearwards to its initial position. As the gate arms 15 95 descend the cables 32 are drawn upwards and move the trip 52 out of the depression 56 into a loaded position. When the train passes the trip 52, it moves this trip forwards to its original position and such motion is transmitted thru the cables 32 for 100 raising the gate elements 15.

105 The stop signs 31 and 39 are preferably coated with illuminous material, such as radium, to make the signs visible also during the night.

110 It is understood that while I have described this automatic railroad gate as having pivoted arms at both sides of tower, it is to be understood that where the road is narrow at the intersections, a single pivoted arm may be used and the tower may be located at one side of the road instead of at the center.

115 While I have shown and described the preferred embodiment of my invention, it is to be understood that I do not limit myself to the precise construction herein disclosed and the right is reserved to all changes and modifications coming within the scope of 120 the invention as defined in the appended claims.

125 Having thus described my invention, what I claim as new and desire to secure by United States Letters Patent is:

1. In a device of the class described, a hollow tower, arms pivoted thereto and extended in opposite directions and arranged to assume vertical and horizontal positions, end portions from the arms projecting into 130

the tower, a platform supported thereby, a rod projecting from the platform, and a stop sign secured to the end of the rod and arranged to be visible when the arms assume 5 the horizontal position, and hidden in the vertical position of the arms.

2. In a device of the class described, a hollow tower with side openings, arms pivoted thereto and extended in opposite directions and arranged to assume vertical and horizontal positions, end portions from the arms projecting into the tower, a platform supported thereby, a rod projecting from the platform, and a stop sign secured on the 10 end of the rod and arranged to be visible thru the said openings when the arms as-

sume the horizontal position, and hidden in the vertical position of the arms.

3. In a device of the class described, a hollow tower with side openings, arms pivoted thereto and extended in opposite directions and arranged to assume vertical and horizontal positions, end portions from the arms projecting into the tower, and a stop sign supported on the said end portions and 20 arranged to be visible thru the said openings when the arms assume the horizontal position, and hidden in the vertical position of the arms. 25

In testimony whereof I have affixed my 30 signature.

GIUSEPPE GUARNIERI.
